Alexis V. Lapteff, New York, N. Y., assignor to The Esterbrook Steel Pen Manufacturing Co., Camden, N. J., a corporation of New Jersey

Application August 31, 1939, Serial No. 86,990

Term of patent 14 years

To all whom it may concern:

Be it known that I, Alexis V. Lapteff, a citizen of the United States of America and a resident of New York, county and State of New York, have invented a new, original, and ornamental Design for a Pencil Clip or Similar Article, of which the following is a specification, reference being had to the accompanying drawing, forming a part thereof.

Figure 1 is a perspective view of the pencil clip or similar article showing my new design;

Fig. 2 is a side elevation;

Fig. 3 is a plan view, and

Fig. 4 is a front elevational view of the same.

I claim:

The ornamental design for a pencil clip or similar article, substantially as shown.

ALEXIS V. LAPTEFF.
